UNITED STATES PATENT OFFICE.

CHARLES W. KIRKPATRICK, OF NEW YORK, N. Y.

MONEY-RECEPTACLE.

1,378,682.

Specification of Letters Patent. Patented May 17, 1921.

Application filed February 11, 1920. Serial No. 357,797.

To all whom it may concern:

Be it known that I, CHARLES W. KIRKPATRICK, a citizen of the United States, residing at New York, in the county of New York and State of New York, have invented certain new and useful Improvements in Money-Receptacles; and I do hereby declare the following to be a full, clear, and exact description of the invention, such as will enable others skilled in the art to which it appertains to make and use the same.

This invention relates to money receptacles and contemplates more particularly what is generally known as a savings bank auxiliary.

An object of this invention is to produce a relatively large money bank with an exterior surface free from all evidence of locking devices, which could be manipulated or tampered with fraudulently.

Another object of the invention is the production of a savings bank auxiliary designed primarily for use in connection with banking institutions wherein the key or locking device of the auxiliary is retained by the officials of the banking institution.

Another object of this invention is to produce a multi-compartment money receptacle in which the locking devices of adjacent compartments are controlled by a key inserted through a relatively small opening in the compartment next to it.

Another object of the invention is the production of a money receptacle in which the locking device is operated to release the cover by an outward or withdrawal movement of the key.

With these and other objects in view, the invention further consists in the arrangement and construction of the several parts hereinafter described and pointed out in the appended claims.

In the accompanying drawings:

Figure 1 is a perspective view of my improved money receptacle illustrating the usual coin slots and additional openings for the deposit of currency;

Fig. 2 is a vertical sectional view on the line 2—2 of Fig. 1;

Fig. 3 is a vertical, longitudinal, sectional view on the line 3—3 of Fig. 1, the receptacle being inverted and the key for operating the same being shown in position;

Fig. 4 is a detail sectional view on the line 4—4 of Fig. 3; and

Fig. 5 is a detail sectional view on the

line 5—5 of Fig. 3, showing the key in position for unlocking the bank.

This invention has been primarily designed as a convenient means for saving money in which the members of a household may severally and individually contribute. For example, the two compartments shown may be divided in such a way as to be used respectively by the parents and children. It may be retained in a household by means of a chain and lock to prevent its removal.

Referring particularly to the drawings in which corresponding reference characters designate similar parts, the money receptacle comprises a casing 1 of relatively smooth and lock-free exterior finish. The casing is made of suitable metal and is divided into compartments 2 and 3 by means of a partition 4. Coin receiving openings 6 and 7 are provided for each compartment respectively, and as shown, are normally closed by means of a pivoted plate 8 against which a relatively strong spring 9 bears, as shown in Fig. 2. This spring 9 is preferably covered or shielded as shown to prevent the money interfering with its operation. Openings 10 and 11 are provided in one wall of the casing and are designed to receive paper money or currency which may be rolled or folded and pushed therethrough into the respective compartments as will be understood.

The compartments 2 and 3 are provided with sliding doors or covers 12 and 13, respectively. Each sliding cover is provided upon opposite sides thereof with grooves 14 arranged to engage guides 15 formed on the casing, as clearly shown in Fig. 3. Openings 16 and 17 respectively are provided in the sliding covers, at one end thereof, and are designed to receive the key to be presently described. Finger depressions 18 are provided in each cover to facilitate the withdrawal of the sliding covers when they are released.

The key 19 is formed with a hook end 20 and a finger grip 21 as shown. The openings 16 and 17 in the sliding covers are relatively small and are designed to receive the key 19 as shown in Fig. 3. The key is inserted through one of these openings and is given a partial rotation whereby the hook end is turned into operative position for engagement with the locking mechanism now to be described.

The locking mechanism is carried in a frame section or supporting block 22 which may be riveted, welded, or formed integral with the casing as the case may be. As an alternative construction the frame section or supporting block 22 may be secured within the receptacle by means of substantially concealed pins 23, thereby making the locking mechanism detachable for purposes of inspection. The frame section or supporting block 22 is recessed as at 24 and is designed to receive locking plungers 25 and 26 and actuating levers 27 and 28, respectively. The locking plungers 25 and 26 are vertically movable within the supporting block 22 and are normally held within the recesses 29 and 30 of the sliding covers, by means of springs 31 and 32. Each plunger is cut away as at 33 and is designed to receive one end of the actuating levers, see Fig. 4. The other end of each actuating lever extends within the range of the key 19 as shown in Fig. 3, and is capable of being lifted by the hook end 20 of said key, when it is desired to depress the locking plunger of the adjacent compartment and release the sliding cover. The actuating levers 27 and 28 are pivoted at 34 to the supporting block with their free ends extending into opposite compartments for actuation by the key 19.

In practice, the money receptacles are preferably distributed among those who would save, and the key is retained by the distributor. When it is desired to empty the contents of the respective compartments of the receptacle the distributor is asked to unlock the compartments.

In operation, the key 19 is inserted, for example, through the relatively small opening 16 in the cover 12 of compartment 2 until the hook end 20 thereof is beneath the free end of the actuating lever 28. A partial rotation of the key 19 brings the hook end 20 immediately beneath the free end of the actuating lever 28, and by an outward or withdrawal movement of the key, said actuating lever 28 is rocked upon its pivot 34 and the locking plunger 26 of the adjacent compartment is released from the recess 30 in the sliding cover 13, thereby permitting the cover to be slid from the compartment 3. In like manner the key 19 is inserted through the relatively small opening 17 in compartment 3 and by a similar operation thereof the sliding cover 12 of the adjoining compartment 2 is released and may be slid away for emptying the contents of the receptacle.

While I have shown the money receptacle to be of a relatively large size and rectangular shape, it will be understood that it need not be so limited, and that various changes in the form, shape and construc-

tion may be made without departing from the spirit and scope of my invention. 65

I claim:

1. A money receptacle comprising a casing of lock free exterior finish, having a money receiving opening therein, another opening in said casing, a movable cover for 70 said receptacle, locking means including a spring actuated plunger and interconnected lever located within the receptacle, and a key provided with a hook end designed to be inserted through the aforesaid opening and 75 engage the free end of the aforesaid lever for manipulating the locking mechanism and releasing the cover.

2. A money receptacle comprising a casing having a plurality of compartments in 80 said receptacle, a money receiving opening and a cover for each compartment, locking means located within the receptacle and adapted to interconnect with the cover of each compartment so that a key operable in 85 one compartment will unlock the cover of an adjacent compartment, relatively small openings in the casing communicating with the locking means of each cover, and a key designed to be inserted within one of the 90 relatively small openings for releasing the cover of the adjacent compartment as aforesaid.

3. A money receptacle comprising a casing having a plurality of compartments in 95 said receptacle, a money receiving opening and a cover for each compartment, locking means including a plunger and an interconnected pivoted lever for engaging and retaining each cover in place, relatively small 100 openings in the casing communicating with the end of each lever, and a key designed to be inserted in one of the said small openings for engaging the aforesaid lever whereby upon a withdrawal movement of the key 105 the cover of the adjacent compartment is unlocked.

4. A money receptacle comprising a casing formed with adjacent compartments, a money receiving opening and a cover for 110 each compartment, locking means including a spring pressed plunger and a lever therefor, relatively small openings formed in said casing, and a key adapted to be inserted in said small openings for engaging 115 the end of said lever whereby upon the withdrawal movement of the key the cover of the adjacent compartment will be unlocked.

In testimony whereof I affix my signature, in presence of two subscribing witnesses.

CHARLES W. KIRKPATRICK.
